Primary Examiner — Michael C Stout*Assistant Examiner* — Fritzgerald L Butac*(74) Attorney, Agent, or Firm* — Global IP Counselors, LLP(57) **CLAIM**

The ornamental design for a portable electric circular saw, as shown and described.

DESCRIPTION

FIG. 1 is a front perspective view of a portable electric circular saw in accordance with our new design;

FIG. 2 is a rear perspective view of the portable electric circular saw in accordance with our new design;

FIG. 3 is a front elevational view of the portable electric circular saw in accordance with our new design;

FIG. 4 is a rear elevational view of the portable electric circular saw in accordance with our new design;

FIG. 5 is a right side elevational view of the portable electric circular saw in accordance with our new design;

FIG. 6 is a left side elevational view of the portable electric circular saw in accordance with our new design;

FIG. 7 is a top plan view of the portable electric circular saw in accordance with our new design;

FIG. 8 is a bottom plan view of the portable electric circular saw in accordance with our new design; and,

FIG. 9 is a front perspective view of the portable electric circular saw in accordance with our new design illustrating a state in which a battery is attached to the portable electric circular saw.

The broken line showing of environmental structures in the drawings forms no part of the claimed design.

The broken lines seen in FIGS. 2, 4, and FIGS. 6-9 show portions of a portable electric circular saw which form no part of the claimed design.

1 Claim, 9 Drawing Sheets(56)
